INVENTOR
LAURENCE A. VINCENT

BY
John E. Hubbell
ATTORNEY

UNITED STATES PATENT OFFICE:

LAURENCE ARTHUR VINCENT, OF PLEASANTVILLE, PENNSYLVANIA, ASSIGNOR TO
NEW CASTLE REFRactories COMPANY, OF NEW CASTLE, PENNSYLVANIA, A COR-
PORATION OF DELAWARE.

WARE SUPPORT.

Application filed October 11, 1926. Serial No. 140,780.

The general object of my present invention is to provide an improved construction of tunnel kiln car superstructures. More specifically, the object of my present invention is to provide an improved arrangement and construction of saggers forming a semi-permanent ware holding superstructure for kiln cars.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described preferred embodiments of my invention.

20 Of the drawings:

Fig. 1 is a plan view of part of a kiln car showing the saggers in position;

Fig. 2 is a plan view of one type of sagger;

25 Fig. 3 is a vertical section on the line 3—3 of Fig. 2; and

Fig. 4 is a vertical section on the line 4—4 of Fig. 2.

In the drawings is shown a general arrangement of saggers adapted to form a semi-permanent ware holding superstructure of a kiln car and arranged so that the ware can be loaded on the car from the outside thereof without handling the saggers.

35 In the usual method of loading kiln cars of this type, operating costs are high due to the amount of saggers and ware handled separately and the consequent amount of breakage incurred. The present arrangement is

40 designed to decrease the cost of loading by decreasing the amount of material handled and improving the method of loading.

In the preferred form shown, the car superstructure consists of a multiplicity of adjacent saggers A and B supported in the usual manner on the car body and arranged in similar superposed layers for holding general ware for glost firing or similar heat treatment.

50 The saggers A and B are constructed along the same general lines, any differences in form being due solely to the dimensions of the kiln car bodies and to the necessity of utilizing all the available space. In Figs.

2—4 of the drawings, the specific construction of a sagger of the form A is illustrated.

Each sagger A consists of a refractory body of general U-shaped outline and rectangular cross section. The sagger is constructed with its larger end and top open. When mounted on the car body the bottom of each sagger forms the top cover plate for the corresponding sagger upon which it is mounted. As shown in Fig. 1, each sagger is mounted with its open end adjacent one side of the kiln car in order that the loading can take place at both sides of the car simultaneously.

Each sagger is provided with a bottom plate A' and vertical side walls A² and A³. The side wall A² is substantially straight throughout its length, while the side wall A³ is formed in successive curved portions of decreasing diameter, the last curved section forming the closed end of the sagger. With this arrangement the sagger is adapted to contain table ware such as plates or saucers of different diameters. The side walls A² and A³ are provided at spaced intervals along their length with bosses A⁴ projecting outwardly and extending the entire height of the side walls. The bosses on the side wall A² are opposite corresponding bosses on the wall A³. The wall A³ is provided with a thickened portion A⁵ adjacent the end of each curved portion of the side wall.

A series of vertically spaced triangular holes A⁶ are formed in each boss A⁴ and thickened portion A⁵ in a plane transverse to the wall face. Each of the holes A⁶ is inclined toward the inner wall face, the portion A⁷ near the outer face having its upper face at a greater angle to the outer face of the side walls than the inner portion. The holes in the thickened portions A⁵ extend in a radial plane from the inner curved wall face. In each triangular hole A⁶ is inserted a removable pin or block C of refractory material. The pins C are of triangular cross section and project inwardly and upwardly into the interior of the sagger. The pins are held in position in the holes A⁶ due to the fact that the pin end portions abut the side walls of the sagger due to the greater incline of the outer hole portion A⁷.

The sagger bottoms A' are provided with a series of openings for permitting the circulation of the hot gases in the kiln chamber

through the superposed saggers and around the ware, so that all of the ware will receive substantially the same heat treatment. The openings may be semi-circular as shown at

- 5 D' or circular as shown at D². Each opening is substantially concentric with the plates or saucers located above it.

With this arrangement of saggers on the kiln car, the ware is loaded into the saggers 10 by placing each piece of ware on three of the supporting pins. The use of triangular pins is advantageous as the amount of ware surface in contact with the supports is very small. The arrangement is characterized by 15 the small amount of handling required in the loading operation, which can be entirely done by cheap labor.

While in accordance with the provisions of the statutes, I have illustrated and described the best form of embodiment of my invention now known to me, it will be apparent to those skilled in the art that changes 20 may be made in the form of the apparatus disclosed without departing from the spirit of my invention as set forth in the appended 25 claims and that in some cases certain features of my invention may be used to advantage without a corresponding use of other features.

30 Having now described my invention, what I claim as new and desire to secure by Letters Patent, is:—

1. A ware support for kiln cars comprising a sagger having its top and one end open, 35 ware supporting pins mounted in the side walls of the sagger and spaced openings in the bottom of the sagger for permitting the passage of heating gases.

2. A ware support for kiln cars comprising 40 an open ended U-shaped sagger having a

bottom and side walls, said side walls being provided with bosses, and ware supporting pins removably mounted in said bosses and projecting into the interior of said sagger.

3. A ware support for kiln cars comprising 45 a sagger having a bottom and side walls, vertically spaced inclined slots in said walls, the outer ends of the slots being tapered, and pins removably mounted in said slots.

4. A ware holding super-structure for kiln 50 cars comprising a series of superposed saggers having one end and top open, said open end being adjacent one edge of the car, and removable means for holding ware in said saggers.

5. A support for table ware comprising a U-shaped sagger having a bottom and side walls, one of said side walls being formed in curved steps, vertically spaced ware supporting pins mounted in said side walls at opposite points, and additional pins mounted in 60 said curved side wall.

6. A ware holding superstructure for kiln cars comprising a series of superposed saggers having one end and top open, said open 65 end being adjacent one edge of the car, and vertically spaced triangular pins removably mounted in the side walls of each sagger.

7. A ware holding superstructure for kiln cars comprising a series of superposed U-shaped saggers having one end and top open, 70 said open end being adjacent one edge of the car, a flue opening in the bottom of each sagger, vertical bosses on the side walls of each sagger, and ware supporting pins removably 75 mounted in said bosses.

Signed at Cleveland in the county of Cuyahoga and State of Ohio this seventh day of October, A. D. 1926.

LAURENCE ARTHUR VINCENT.
